UNITED STATES PATENT OFFICE.

JOHN HERMAN, OF PHILADELPHIA, PENNSYLVANIA.

TRUNDLING TOY.

Application filed January 26, 1922. Serial No. 532,004.

To all whom it may concern:

Be it known that I, JOHN HERMAN, a citizen of Poland, residing at Philadelphia, in the county of Philadelphia and State of Pennsylvania, have invented certain new and useful Improvements in Trundling Toys, of which the following is a specification.

This invention relates to certain new and useful improvements in trundling toys and has particular reference to a toy having a wheel supported axle with a cage or car carrying a figure toy journaled on the axle engaging one of the wheels to cause rotation thereof, a handle bar being fixed to the axle to prevent rotation of the axle.

A further object of the invention resides in the provision of a toy of the trundling type wherein an axle supporting the wheels has a handle secured thereto with a cage journaled on the handle and spring pressed into engagement with the wheels to cause rotation of the cage during the trundling movement of the toy.

With the above general objects in view and others that will appear as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a side elevational view of a trundling toy constructed in accordance with the present invention, showing the cage rotatably supported on the handle and spring pressed into frictional engagement with the trundling wheels,

Figure 2 is a side elevational view of the device, showing the rotatable cage in perspective and the car rotatably supported on the axle with the peripheral edge thereof frictionally engaging one of the trundling wheels, and

Figure 3 is a fragmentary detail view, of the trundling wheels, the axle carried thereby and the car rotatably supported on the axle with one of the trundling wheels spring pressed into frictional engagement with the car.

Referring more in detail to the accompanying drawing there is illustrated a trundling toy embodying a block axle 1 rectangular in cross section as shown in Fig-

ure 1, the same being supported on trundling wheels 2 and 3 through the medium of screw pins 4 having plain portions upon which said wheels are journaled with the threaded ends of the screw pins engaging or received in the opposite ends of the block axle, this construction being clearly shown in Fig. 3. The heads of the screw pins 4 extend a considerable distance outwardly of the wheels 2, each having mounted thereon a pair of disk washers 5 with a coil spring 6 surrounding the screw pins between the washers to force one of the washers into engagement with the heads of the screw pins and also to move the wheels 2 and 3 in a direction toward the block axle 1. As shown more clearly in Fig. 3, a washer 7 is interposed between the wheel 3 and the block axle 1 to limit the movement of the wheel 3 toward said axle.

A relatively long handle 8 has one end thereof secured in an opening 9 formed in the block axle, the same being retained in position by the screw pins 4 associated with the wheel 3 entering the same from one side thereof, as shown in Fig. 3.

A car or receptacle is supported on the block axle 1 for rotation, the same embodying a disk 10 having an axial opening 11 for the free reception of the upper end of a screw 12 that is threaded into the block axle 1, the peripheral edge of the disk 10 extending laterally of one end of the block axle 1 as shown in Fig. 3 for frictional engagement with the adjacent face of the trundling wheel 2, the spring 6 upon the screw pin 4 adjacent the wheel 2, moving said wheel into frictional engagement with said disk. The car or receptacle embodying the base disk 10 carries a wire or other side wall portion 13 within which a figure toy is mounted.

A rotatable cage is journaled on the handle bar 8, the same embodying a pair of spaced disk portions 15 connected by rails 16 adjacent the periphery of said disks, the handle bar 8 being connected to the block axle 1 to one side of the transverse center thereof to cause the disk 15 of the cage adjacent the axle to frictionally ride upon the periphery of the trundling wheel 3 as clearly shown in Figs. 1 and 2. To hold the cage in frictional engagement with the wheel 3, a coil spring 17 surrounds the handle bar 8 adjacent the inner face of the lower disk 15, the upper end of the spring being secured

as at 18 to said handle bar while the lower end of the spring freely engages the disk washer 19 interposed between the spring and the lower disk 15.

5 From the above detail description of the device it is believed that the construction and operation thereof will at once be apparent, it being noted that the car or receptacle embodying the base disk 10 is rotatably mounted upon the block 1 to present the periphery of the disk for frictional engagement with the spring pressed trundling wheel 2. The handle bar 8 also being connected to the block axle 1 laterally of the 10 transverse center thereof, the lower face of the bottom disk 15 is presented for frictional engagement with the periphery of the trundling wheel 3. Considerable amusement is derived by children during the trundling 15 movement of the toy, the car being rotated and carrying therein a figure toy of the desired configuration, while the cage embodying the disk 15 and the connecting rails or bars 16 is rotatable upon the handle bar 8. Efficiency in the operation of the 20 toy, is enhanced by the spring elements 6 and 17 associated with the screw axle pin 4 and the handle bar 8, maintaining frictional engagement between the relatively 25 rotatable elements.

30 While there is herein shown and described the preferred embodiment of the present invention, it is nevertheless to be understood that minor changes may be made therein without departing from the spirit and scope 35 of the invention as claimed.

What is claimed as new is:—

1. In a trundling toy of the type described, a block axle, trundling wheels journaled 40 thereon, the bearings for said wheels including screw pins engaging in the opposite ends of the block axle, coil springs on said screw

pins interposed between the outer ends of the pins and the outer faces of the trundling wheels normally to force the wheels in directions toward the block axle, a car embodying a disk base rotatably mounted on the block axle at one side of the center thereof to present the periphery of said disk for frictional engagement with the adjacent 45 inner face of one of the trundling wheels, a handle bar fixed to the block axle, and a cage journaled on the handle bar and having a lower disk portion overlying one of the trundling wheels for frictional engagement 50 therewith to effect rotation of said cage.

2. In a trundling toy of the type described, a block axle, trundling wheels journaled thereon, the bearings for said wheels including screw pins engaging in the opposite ends 55 of the block axle, coil springs on said screw pins interposed between the outer ends of the pins and the outer faces of the trundling wheels normally to force the wheels in directions toward the block axle, a car embodying a disk base rotatably mounted on the block axle at one side of the center thereof to present the periphery of said disk for frictional engagement with the adjacent inner face of one of the trundling wheels, a handle bar fixed to the block axle, a cage journaled on the handle bar and having a lower disk portion overlying one of the trundling wheels for frictional engagement 60 therewith to effect rotation of said cage, and a coil spring surrounding the handle bar having one end anchored to the handle bar and the other end thereof freely engaging the disk of said base to force the cage into frictional engagement with the 65 trundling wheel.

In testimony whereof I affix my signature.

JOHN HERMAN.
